L. DONAHUE.

TELLER'S WINDOW FOR BANK PARTITIONS.
APPLICATION FILED APR. 7, 1919.

1,314,513.

Patented Sept. 2, 1919.

By William Colinton
Attorney

UNITED STATES PATENT OFFICE.

LEONARD DONAHUE, OF VERDUN, QUEBEC, CANADA.

TELLER'S WINDOW FOR BANK PARTITIONS.

1,314,513.

Specification of Letters Patent.

Patented Sept. 2, 1919.

Application filed April 7, 1919. Serial No. 288,155.

To all whom it may concern:

Be it known that I, LEONARD DONAHUE, a subject of the King of Great Britain, residing at Verdun, Province of Quebec, Canada, have invented certain new and useful Improvements in Tellers' Windows for Bank Partitions; and I do hereby declare that the following is a full, clear, and exact description of the invention, such as will enable others skilled in the art to which it appertains to make and use the same.

This invention relates to tellers' windows for bank partitions and the principal object thereof is to provide a window that is bullet proof, at the same time the cashier and customer being visible to each other, and wherein means are provided for readily passing money from the teller to the aforesaid customer.

Another object of the invention resides in the provision of means, whereby conversation may be distinctly carried on between the two parties, and for lighting the window.

A further object of the invention is to provide a bullet proof counter for the prevention of shooting under the window.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claims without departing from the spirit of the invention or sacrificing the efficiency of the same.

Further objects will be apparent from the following specification, appended claims and drawing, in which,

Figure 1 is an elevational view of my improved device attached to the bank partition;

Fig. 2 is a vertical sectional view on line 2-2 of Fig. 1;

Fig. 3 is a detail sectional elevational view of a portion of the partition glass;

Fig. 4 is a cross sectional view of a modification of the partition glass;

Figs. 5 and 6 are diagrammatical views of the positions that may be assumed by the windows; and,

Fig. 7 is a diagrammatical view of a modified form of a window with double glasses therein.

Referring now more particularly to the accompanying drawings wherein like and corresponding parts are designated by similar reference characters throughout the several views, the numeral 1, designates the partition proper which is channeled for the reception of the glass window 2.

Disposed between the window 2 and the panel 3 of the partition 1, is the dome 4, in which are mounted the incandescent lamps 5, the latter being so positioned to throw the light downwardly toward the counter. This dome is secured to the panel 3 by screws and the glass 2 carries an upper frame 6 and lower frame 7.

A counter 8 is provided with a longitudinal concaved portion 9 and is covered with a sheet of some soft metal, such as zinc or lead, so that the money passed thereover will have a tendency to slide easily thereover.

The glass window 2, is supported at the side edges in the partition channels and is connected to the dome 4, by a strip of wire 85 netting 10, which is secured to the frame 6 of the window and fastened to the dome by screws.

The lower frame 7 of the glass window 2 is positioned centrally of the concaved portion 9 of the counter and spaced therefrom to form an opening to allow money or papers to be passed thereunder.

By this construction the teller and customer are at all times visible to each other and conversation carried on, will pass through the wire netting 10. To render the glass window bullet proof, I have molded in the same the reinforcing wires 11, so that should the teller be fired at the said wires 11, would deflect the bullet.

To prevent the shooting of the teller under the window or through the counter, I provide a sheet of steel 12, which latter is disposed between the counter 8 and the sill 13, so that a bullet fired under the window, will pass through the soft metal and impinge against the steel sheet 12.

A modified construction of the window is illustrated in Fig. 4, in which the latter is composed of a number of sections 14, which are separated by the flat bars 15 and the

strips 16 have portions overlying the glass sections 14 at their point of connection with the bars 15 and screws 17, hold the strips onto the said bars.

5 The glass window may be positioned in a vertical plane as illustrated in Fig. 5, or on a diagonal plane illustrated in Fig. 6.

A further modification illustrated in Fig. 7, provides for two divergently mounted 10 sheets of glass 18 and 19, between which is disposed a center sheet 20.

It is obvious that the teller is at all times protected from the gun play of a robber and at the same time perfect vision and 15 hearing is maintained between the teller and the customer.

Having thus fully described my invention, what I claim as new and desire to secure by Letters Patent is:

20 1. A teller's window for bank partitions, comprising a counter having a concaved portion therein, a sheet of glass mounted in the partition and having one end projecting within the concaved portion of said counter, 25 and a lighting dome secured to said glass.

2. A teller's window for bank partitions, comprising a counter having a concaved portion therein, a sheet of glass mounted in the partition and positioned within the said 30 concaved portion of the counter and having its lower end spaced from the same, a dome secured to said partition and spaced from said glass, wire netting disposed in said space and secured to said dome and glass, 35 and bars arranged in said glass for reinforcing same.

3. A teller's window for bank partitions, comprising a counter and having a concaved channel extending the length thereof, a sheet of glass mounted in said partition and having its lower end extending within and spaced from the bottom of said channel, a dome secured to said partition and disposed above the said glass, incandescent globes arranged in said dome for directing light toward the said glass, a screen secured to the dome and glass, through which conversation is adapted to pass from one side of the window to the other. 40

4. A teller's window for bank partitions, comprising a counter, a glass mounted in said partition above said counter, said glass having reinforcing bars mounted therein and a lighting dome connected with said glass and providing a space through which 55 conversation is adapted to pass from one side of the glass to the other.

5. A teller's window for bank partitions, comprising a sheet of reinforced glass mounted therein, a counter arranged in said 60 partition and formed with a channel, the said glass having its lower end projecting within but spaced above the bottom portion of said channel, a dome secured to the partition and glass and positioned to form 65 a space between the glass and dome, and a steel plate mounted on said counter.

In witness whereof I have hereunto set my hand.

LEONARD DONAHUE.
